UNITED STATES PATENT OFFICE.

ERNST KOPKE, OF HONOLULU, TERRITORY OF HAWAII.

CENTRIFUGAL SEPARATOR.

Application filed November 30, 1925, Serial No. 72,347. Renewed December 23, 1927.

The invention relates to certain improvements in centrifugal separators of the general type disclosed in my prior patent No. 1,119,176, dated December 1, 1914, and 5 has for its object to provide the rotor with a gradually inclined interior surface between the side walls and the bottom, which will prevent the packing of the solid or gritty material between the annular guide 10 plate and the wall of the rotor, and also to construct the perforated screen or foraminated support for the annular guide plate of telescoping sections to permit the vertical adjustment of the annular plate and thereby 15 vary the space separating the periphery of the latter from the wall of the rotor, in accordance with the character of the material being separated, liquors carrying a large portion of gritty material requiring a larger 20 opening or space between the edge of the guide plate and the adjacent wall of the bowl or rotor than would liquors carrying slimy, colloidal or flocculent solid material.

The invention is illustrated in the accompanying drawings, in which:—

Fig. 1 is a sectional elevation of a centrifugal separator, involving the improvements. Fig. 2 is a fragmentary sectional elevation 25 of the lower part of the bowl or rotor, illustrating the improvements in detail.

Referring to the drawings, 1 represents the wall of the stationary casing of the separator, 2 the upper flange and 3 the lower flange or curb, constructed and arranged as 30 in the patent aforesaid.

The rotor or bowl comprises a cylindrical wall 4, connected to a relatively flat bottom 5 by means of a gradually inclined interior wall section 6, which may be either plain or 35 curved, the essential purpose of this inclined surface being to cause the solid material or mud to be forced over the same in an outward and upward direction into the separating chamber and prevent the accumulation or packing of the mud in this portion 40 of the bowl as inevitably occurs when the joint between the side wall and the bottom of the bowl forms a right angle.

Mounted above the bottom or lower flange 5 and concentric with the bowl is an imperforated guide plate, which may take any 45 of the general forms shown in my prior patent aforesaid, but which preferably comprises a flat section 10 with a downwardly inclined or conical marginal flange 10', the peripheral edge of which projects toward

the curved or inclined surface 6 and defines an annular space through which the materials to be separated are forced by the 60 centrifugal action.

As hereinbefore indicated, it is necessary and desirable that this annular space be adjustable as to size or area to insure effective and uniform separation of various types or characters of mixtures of solid and liquid 65 materials and, to effect this object, the guide plate 10 is vertically adjustable with respect to the bottom or lower flange 5, so that the distance between the peripheral edge of the plate and the curved or inclined 70 wall 6 may be varied at will, as graphically illustrated at α and α' in Fig. 2.

The preferred means for vertically adjusting the plate 10 comprises two annular telescoping foraminated plates or screens 11 and 11', the former being connected to the bottom 5 by suitable bolts and the latter being secured by any appropriate means to the under face of the guide plate 10, said telescoping screens being secured together in any desired relative vertical adjustment 75 by means of bolts 13, which are passed through registering openings in the telescoping screens, as clearly illustrated in Fig. 2.

In operation, the rough liquor, containing solid impurities, flows through the nozzle 21 into the accelerating chamber defined by the guide plate 10 and is driven by centrifugal force through the perforations in the telescoping screen sections 11 and 11' and is accelerated to the circumferential velocity existing at this point. It is further accelerated through skin friction in the constricted opening between the peripheral edge of the guide plate 10 and the adjacent inclined or curved wall 6 of the bowl. The solid impurities, which are heavier than the liquor, will at once tend to deposit on the wall of the bowl, which would have the effect of gradually closing the space or opening between the peripheral edge of the guide plate and the adjacent wall of the bowl, but, by reason of the gradual inclination or curvature of the surface 6, the solid material is forced upwardly and into contact with the inner cylindrical wall of the bowl, leaving the annular space practically unobstructed, so that the flow from the accelerating chamber into the separating chamber is maintained substantially uniform until the accumulation of solid material becomes so

great as to necessitate stopping the operation and cleaning the bowl. As hereinbefore stated, the annular space between the peripheral edge of the guide plate 10 and the adjacent inclined or curved surface 6 of the bowl is regulated in accordance with the character of the solid material carried by the liquor and this regulation is effected by adjusting the perforated plates or screens 11 and 11' relatively to each other to raise or lower the guide plate, two adjustments of the latter being indicated in full and dotted lines in Fig. 2. In all other respects, the apparatus is operated in the usual manner as described in my prior patent aforesaid, but the particular improvements hereinbefore described insure a uniform rate of flow of unseparated liquor, which means an increased rate of uniform separation, and at the same time effects a more uniform distribution of the mud throughout the entire height of the separating chamber and the total avoidance of the tendency of the mud to pack in the lower portion of the latter and thereby obstruct the flow of the material from the accelerating chamber into the separating chamber.

What I claim is:

1. A centrifugal separator comprising a rotatable bowl having a cylindrical wall merged into the bottom by an inwardly inclined surface, an annular guide plate defining an antechamber adjacent said inclined surface, and means for adjusting said guide plate vertically to vary the space between the periphery of the same and said inclined surface.

2. A centrifugal separator comprising a rotatable bowl having a cylindrical wall merged into the bottom by an inwardly inclined surface, an annular guide plate defining an antechamber adjacent said inclined surface, and a vertically adjustable foraminous support for said guide plate, whereby the space between the periphery of said plate and the inclined surface may be varied.

3. A centrifugal separator comprising a rotatable bowl having a cylindrical wall merged into the bottom by an inwardly inclined surface, an annular guide plate defining an antechamber adjacent said inclined surface, telescoping annular screens supporting the annular plate, and means for relatively adjusting the annular screens to vary the elevation of the annular plate and the space between the periphery of said plate and said inclined surface.

4. A centrifugal separator comprising a rotatable bowl having a cylindrical wall merged into the bottom by an inwardly inclined surface, an annular guide plate defining an antechamber adjacent said inclined surface, telescoping annular screens supporting the annular plate, and bolts for securing the annular screens in different relative vertical adjustments to vary the elevation of the annular plate and the space between the periphery of said plate and said inclined surface.

In testimony whereof I affix my signature.

ERNST KOPKE.
